UNITED STATES PATENT OFFICE.

JOHN ANDREW TITZEL, SR., OF FRANKLIN, PENNSYLVANIA, ASSIGNOR OF
ONE-THIRD TO JAMES C. TITZEL, OF GLENSHAW, PENNSYLVANIA.

ELECTRIC MOTOR OR GENERATOR.

SPECIFICATION forming part of Letters Patent No. 718,588, dated January 13, 1903.

Original application filed December 13, 1900, Serial No. 39,628. Divided and this application filed March 26, 1902. Serial No. 100,044. (No model.)

To all whom it may concern:

Be it known that I, JOHN ANDREW TITZEL, Sr., a citizen of the United States, and a resident of Franklin, in the county of Venango and State of Pennsylvania, have invented a new and Improved Electric Motor or Generator, of which the following is a full, clear, and exact description.

My invention relates to electric devices capable of use either as motors or as generators, and has for its object the production of a strong and uniform magnetic field, so that the apparatus will be very efficient in either of its capacities.

15 This application is a division of another application formerly filed by me—to wit, Serial No. 39,628, filed December 13, 1900.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in both the figures.

25 Figure 1 is a side elevation of my device, and Fig. 2 is a central vertical section through the same.

As shown in the figures mentioned, the apparatus comprises a frame 1, with plates 2 for holding the field magnets and coils 3 4. These coils are arranged in two sets, and within each set the field-coils are equidistant; but adjacent or end coils of different sets are arranged unsymmetrically. Thus there are shown eight field-coils—viz., four coils 3 and four coils 4. The angle separating adjacent coils of the same set is $360 \div 8 = 45$ degrees; but at the top the adjacent coils 3 and 4 form

30 an angle of $1\frac{1}{2} \times \frac{45}{2} = 33\frac{3}{4}$ degrees, and at the bottom of the angle separating the end coils 3 and 4 is $2\frac{1}{2} \times \frac{45}{2} = 56\frac{1}{4}$ degrees. Generically

35 speaking, the angle separating such coils should be equal to an uneven multiple of one-fourth of the angle separating adjacent field-coils of the same set—that is, in the present

40 case $\frac{45}{4} = 11\frac{1}{4}$ degrees. The field-magnets have 45 reduced pole-pieces 5 6, corresponding to simi-

lar pole-pieces 7 8 of the armature-magnets, the magnets 9 10 of which are arranged in two sets, the coils of one set alternating with those of the other set. The number of armature-coils is equal to twice the number of field-coils—that is, sixteen in the present case—and the armature-coils are evenly spaced—that is, adjacent coils from an angle of twenty- 60 two and one-half degrees or one-half of that separating adjacent field-coils of the same set. The reduced pole-pieces 5 6 of the field-magnets are about equal in width to the spaces between the reduced pole-pieces 7 8 of adjacent armature-magnets. Owing to the symmetrical arrangement of the two sets of field-coils 3 4 the field-coils 4 will be half-way between armature-coils when the field-coils 3 register with the armature-coils, as shown in 70 Fig. 1, and vice versa. The armature-coils are mounted on a support 11, rotating with the shaft 12, which also carries a commutator having thirty-two sections—that is, twice as many as there are armature-coils. Alternate 75 sections 13 are unconnected or made of insulating material, and between said sections are located conducting-sections 14 15 in regular alternation. Of these the sections 14 are connected by wires 16 with one end of each coil 9, 80 while wires 17 similarly connect the sections 15 with one end of each coil 10. The other end of each coil 9 is connected by a wire 18 with the wire 16 of the adjacent coil 9, and similarly the other end of each coil 10 is connected by 85 a wire 19 with the wire 17 of the adjacent coil 10. The field-coils 3 4 should be wound so as to produce the same polarity at the inner ends of the field-magnets. The coils of each set are connected in series by wires 20 21, and 90 one end of each wire is connected with the binding-post 22, to which leads the feed-wire 23, while the other ends of the wires 20 21 are connected with upper brushes 24 25, respectively, engaging the commutator at points 95 distant from each other about twelve degrees, (eleven and one-fourth degrees is the exact distance found by calculation.) To secure contra-clockwise rotation, these brushes should be in the position shown by full lines 100 in Fig. 1. It will be seen that this connects the brush 24 with that armature-coil which is nearest to the uppermost field-coil 3 in its movement toward said coil, and the brush 25

is connected with that armature-coil which is nearest the uppermost field-coil 4 in its movement toward said coil. At the bottom the commutator is engaged by two similar brushes 24 25, likewise located at eleven and one-fourth degrees from each other. These lower brushes are both connected by wires 26 27 with the binding-post 28 and are so arranged that they will connect with those armature-coils which 30 are nearest the lowermost field-coils 3 and 4, respectively. A feed-wire 29 leads to the binding-post 28. In the position shown in Fig. 1 the following circuit is just being broken: wire 29, post 28, wire 26, brush 24, a 35 sector 14, thence dividing into parallel and passing through wires 16 and 18 to the right and left of the figure, thence upward through those of the armature-coils numbered 9 to another sector 14, thence through upper brush 24, and downward through the left-hand field-magnet 3 to post 22 and wire 23. The following circuit is just being closed: wire 29, post 28, wire 27, brush 25, a sector 14, wires 16 and 18, coils 9, disposed to the right and left, upper 40 sector 14, upper brush 25, and downward through right-hand field-coils 4 to post 22 and wire 23—that is to say, as the upper sector 14 is disengaging the upper brush 24 and engaging the brush 25 the left-hand field, made up of magnets 3, is being deenergized, and the right-hand field, made up of magnets 4, is just beginning to be energized. This transition occurs when the field and armature magnets are in the relative position shown, the 45 left-hand field-magnets being in juxtaposition with adjacent armature-magnets 3, and the right-hand field-magnets being a little in advance of the adjacent magnets 9. With the parts in the position shown the magnets of the left-hand field have just ceased to attract the armature-coils 9 adjacent and the right-hand field-magnets are just commencing to draw the armature-coils 9 to which they are 50 adjacent, so that the rotation of the armature is continued in the same contra-clockwise direction. As soon, however, as the armature rotates a little farther, so that the right-hand field-coils 4 are brought into juxtaposition with such of the armature-coils 9 as are immediately adjacent thereto, the sectors 14 are succeeded by the sectors 15, so that the current flows through armature-coils 10 instead of 9, the circuits being otherwise the same—that is, during the rotation immediately preceding the reaching of the position shown in Fig. 1 the motor has been driven contra-clockwise by the attraction of the field-coils 4 upon as many armature-coils 9. Immediately after reaching said position the motor 55 is driven in the same direction by the attraction of the field-coils 3 upon as many armature-coils 9. Then follows a period during which the field-coils 4 are energized simultaneously with as many armature-coils 10, and, finally, the four field-coils 3 attract as many armature-coils 10. Each of these periods corresponds to a rotation of the armature

through an angle of eleven and one-fourth degrees. The armature is supported upon a shaft 30 in the usual manner. A regular alternation in magnetic attraction is thus obtained. It will of course be understood that the armature-coils are all wound so as to give the armature-magnets the same polarity, which should be the opposite polarity to that of the field-magnets. 70 75

To reverse the motor, the brushes 24 25 should be shifted around the commutator in a contra-clockwise direction through an angle of eleven and one-fourth degrees, thus 80 bringing the brushes 24 to the position shown for the brushes 25 and the latter to the position shown by dotted lines. To enable the brushes to be thus shifted, they would be mounted on a carrier, as shown in the other 85 view, having a limited turning movement about the axis of the commutator.

I prefer to make the conducting commutator-sections 14 15 of a slightly-greater width than the distance between adjacent brushes 90 24 25, so that said brushes will for a moment both engage the same section 14 15, thus making one circuit before the preceding circuit is broken, and prevent sparking.

The apparatus is reversible—that is, it may 95 be used as a dynamo or generator for the production of a continuous current. Further, the apparatus may be employed as an alternating-current generator. For this purpose a source of electricity would be connected 100 with the binding-posts 22 28 to energize the field-coils 3 4 and power would be applied to turn the armature. An alternating current could then be taken off from the top brushes 24 25 to one binding-post and the bottom 105 brushes to the other binding-post. Finally, I may use the apparatus as an alternating-current motor. The motor will start in any position, whether used with a direct current or an alternating one, and in the latter case 110 the motor will synchronize itself with the generator driving it. The motor can be operated in either direction. The motor can also be constructed as a twin motor, as shown in Fig. 2. 115

Having thus described my invention, I claim as new and desire to secure by Letters Patent—

1. An electric motor or generator, comprising a rotary armature, a commutator therefor, and a fragmentary field comprising separate sets of field-magnets, the magnets in each set being equally spaced apart and the two sets being so disposed that the nearest magnets in adjacent sets are spaced apart by a different distance from the spaces between adjacent magnets in a set, and means for supplying a current to said armature and said field-magnets. 120 125

2. An electric motor or generator, comprising a rotary armature, a commutator therefor and a fragmentary field comprising separate sets of field-magnets, the magnets in each set being spaced symmetrically as re-

gards a common center and the sets being spaced symmetrically as regards said center, a set of brushes arranged to engage the commutator, each brush being connected with 5 one set of field-coils, and another set of brushes connected with the feed-wire and engaging said commutator at points substantially opposite the first-named brushes, another feed-wire being connected with said 10 sets of field-magnets.

3. An electric motor or generator, comprising two sets of coils, viz: stationary or field coils, and rotary or armature coils held to move in unison, the number of field-coils being 15 different from that of the armature-coils and spaced apart asymmetrically, a commutator stationary in relation to the armature-set of coils and having as many evenly-spaced conducting-sections as the said set has coils, 20 connections from one end of each coil of said set to one of the commutator-sections, spaced brushes stationary relatively to the other set of coils and engaging the commutator, and connection for supplying current to the armature-coils and field-coils respectively. 25

4. An electric motor or generator, compris-

ing two sets of coils, viz: stationary or field coils and rotary or armature coils held to move in unison, the number of armature-coils being in excess of that of the field-coils, 30 a commutator stationary in relation to the armature set of coils and having as many evenly-spaced conducting-sections as the said set has coils, each section being connected with one end of a coil of said set, and 35 the length of each commutator-section corresponding to one-half of the angle separating adjacent coils of said set, said field-coils being divided into semicircular groups, and said groups being arranged asymmetrically, spaced 40 brushes stationary relatively to the field set of coils and engaging the commutator, and connections for supplying current to the armature-coils and the field-coils respectively. In testimony whereof I have signed my 45 name to this specification in the presence of two subscribing witnesses.
